HINGE

Herbert Traumüller, Brooklyn, N. Y.

Application January 27, 1944, Serial No. 519,955

7 Claims. (Cl. 16—159)

This invention relates to hinges adapted for use in hingedly coupling box or case parts composed of light or relatively thin materials of various kinds and classes. More particularly the invention relates to hinges having substantially similar butt parts including at end portions thereof L-shaped flanges for securing the butts to the respective supports, and further, in utilizing one of the flanges at each end of the respective butts as a means for keying and retaining the butts against displacement from their respective supports.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a face view of the hinge side of a box and cover coupled together with one of my improved hinges.

Fig. 2 is a partial section on the line 2—2 of Fig. 1, on an enlarged scale.

Fig. 3 is a partial section on the line 3—3 of Fig. 1.

Fig. 3—A is a view similar to Fig. 3, showing only a part of the construction and showing a modification.

Fig. 4 is a section on the line 4—4 of Fig. 1; and

Fig. 5 is a section taken through the central portion of the hinge, as seen in Fig. 1, showing the adaptation of a spring member to the hinge in forming a spring hinge construction.

The present application is a continuation in part of the structure disclosed in my prior application Serial Number 499,351, filed August 20, 1943, and matured into Patent No. 2,343,593 of March 7, 1944. The present application is directed to a hinge structure adapted primarily for use in connection with thin walled articles, boxes, cases and the like, and wherein the hinge butts are disposed on an outer surface of the parts to be hingedly coupled. For example, the box and the cover therefor.

With this type of construction the hinge butts are produced with L-shaped end coupling flanges of such dimensions as to incorporate in one flange a length equivalent to or substantially equivalent to the thickness of the wall of the support in connection with which it is to be mounted, and the other angularly extending flange being adapted to be forced into and imbedded in the inner surface of said wall of the support in

securing and keying the butt against displacement from the wall. Thus dispensing with the use of screws, nails and other fastening devices commonly employed in mounting hinges of the class under consideration in position.

Furthermore, where the wall structure of the support is composed of relatively hard material in comparison with a soft wood or soft plastic material, the last mentioned key flange may include a prong for piercing the wall structure to insure firm and definite mounting of the butt in connection therewith. This type of construction would also be desirable where excessive crimping of the keying flange would not be desirable.

In the present illustration, the size of the hinge and box and cover parts have been exaggerated for sake of clarity. In Figs. 1 and 2, 10 can be said to represent a box or case part, and 11 a cover hingedly coupled therewith by one of my improved hinges 12.

The hinge 12 comprises two substantially similar butt parts 13 and 14, each having at one edge thereof curled cylindrical bearings 15 and 16, three being employed on each butt. It will thus be seen that one hinge butt blank will suffice in forming each butt member by simply bringing the cylindrical bearing ends together in the manner clearly illustrated in Fig. 1. The cylindrical bearings are joined by a pintle pin 17, to which one set of bearings 15—16 will be secured in order to retain the pin against accidental displacement.

Each hinge butt terminates at its ends in L-shaped mounting flanges comprising a flange 18 integral with the attaching plate 19 of the butt, and extending at an angle thereto. At the end of this flange is an angularly extending and shorter flange 20, which is normally disposed at an angle to the flange 18, and would assume the dotted line position indicated in Fig. 3 of the drawing.

The flanges 18 are of a length equal to the thickness of the wall structure of the box and cover parts 10—11, and adjacent abutting edges of these parts are slit or cut, as at 21, for a depth at least equal to the width of the flange 18. This provides free mounting of each butt in connection with the supports 10 and 11 with the flanges 20 arranged upon inner surfaces 22 of the supports, after which the flanges 20 are depressed or forced into the supports 10—11, thus forming depressions 23 in the surfaces 22, and this keys and retains the butts against displacement from each support 10 and 11, as will clearly

appear from a consideration of Figs. 3 and 4 of the drawing. In the latter figure, it will be apparent that the wall portions 24 remain on the adjacent surfaces of the parts 10 and 11, which prevent the butts from becoming detached from each support.

In forming the hinge butts, the central portions of the attaching plates 19 thereof are depressed inwardly to form sockets 25, which will register with sockets 26 formed in the supports 10 and 11 to adapt the hinge for the application of spring members whenever desired for providing a spring hinge mounting of the cover part. The spring is not illustrated in Figs. 1, 2 and 3 of the drawing in that it is not essential that the spring structure be employed. However, these socket portions 25 in the butts will strengthen the attaching plate portions thereof, and would not be objectionable except from the standpoint of providing the sockets 26 in the supports to receive these projections.

In Fig. 5 of the drawing a spring 27 is shown coupled with the socket portions 25, and arranged to operate in the sockets 26 of the supports 10 and 11. The spring is arc shaped in form and has hooked ends 28 for engagement with the edges of the inwardly pressed walls 29 of the sockets 25. This type of a hinge structure is known, and serves to support the cover 11 in open, as well as closed positions.

In Fig. 3-A of the drawing is shown a slight modification. In this figure, a portion of one support 30 is illustrated. One end portion of a hinge butt 31 is shown including an angularly extending flange 32, similar in all respects to the flanges 18, and at the end of which is a flange 33 which differs from the flanges 20 simply in the provision of a prong 34 stamped from the material thereof, and extending outwardly so as to become imbedded in the wall structure of the support 30. It will be understood that both ends of each butt will be similarly formed, and in initially producing the butts, the keying flange 33 will be arranged in a position substantially similar to the dotted line position shown in Fig. 3-A, and then forced into the support substantially in the manner indicated in full lines. In this operation the body of the flange 33 may become slightly imbedded in the support, or in some cases, may actually make no material impression in the support. However, it must be borne in mind that in dealing with sheet metal, the thickness of the metal employed in the butt is very thin, and a question of degree of impression or imbedding in receiving a blow, particularly on a support of hard material might in some cases be more or less microscopic. In such cases, the impression in any event would not be sufficient to insure positive mounting of the butt in connection with the support, and from this standpoint, the prong is employed to pierce the support.

Contrary to the foregoing, where the supports are of a softer material, the support may be said to be depressed, and the thin wall flange, as for example 20, is simply forced into this depression in the same operation.

Hinges of the class under consideration may be produced from any kind of material capable of being produced and assembled in the manner described. In this connection plastic materials can be employed. With some plastic materials, it may be found necessary to pre-heat the coupling flanges prior to the assemblage operation, or in the operation of imbedding them in the

support. Further, hinges of the kind under consideration can be mounted in connection with wood, plastic or paper or cardboard supports of various kinds and classes. The hinge being economical in construction adapts itself to uses of the kind mentioned.

It will also be apparent that by changing the size and structure of the butts, the hinges may be used for heavier and more substantial work, but in all instances, the need for using independent fastening devices such as screws, nails or the like is dispensed with.

In assemblage, the two butts may be slipped into the grooves, notches or slits formed in adjacent edges of each support with these edges both disposed upwardly and in a single operation the butts can be secured to both supports in the manner described. However, in some cases, and where deemed advisable, one butt may first be attached to one support, and then attached to the companion support. With all instances, however, the thickness in the wall structures of the supports or at least adjacent edge portions thereof to be hingedly united will be of the same thickness or of a thickness equivalent to the normal spacing of the end flanges from the attaching plates of the respective butts. Or in other words, a thickness substantially equal to the length of the flanges extending at right angles to the attaching plates.

Having fully described my invention, what I claim as new and desire to secure by Letters Patent is:

1. The combination with adjacent wall portions of two supports adapted to be hingedly coupled, with spaced slits on said walls arranged angularly to and opening through adjacent abutting edges of said walls and through inner and outer surfaces thereof, of a hinge comprising two butts having elongated attaching plates, means at adjacent edges of the plates for hingedly coupling the same, said plates being adapted to be mounted on outer surfaces of said supports, the ends of each plate having angularly extending flange portions arranged in said slits and of a length equal to the thickness of the wall portions of the supports, and the inner ends of said flange portions having angularly extending keying flanges overlying and imbedded in inner surfaces of said supports in retaining the butts against displacement from the respective supports.

2. The combination with adjacent wall portions of two supports adapted to be hingedly coupled with spaced slits on said walls arranged angularly to and opening through adjacent abutting edges of said walls and through inner and outer surfaces thereof, of a hinge comprising two butts having elongated attaching plates, means at adjacent edges of the plates for hingedly coupling the same, said plates being adapted to be mounted on outer surfaces of said supports, the ends of each plate having angularly extending flange portions arranged in said slits and of a length equal to the thickness of the wall portions of the supports, the inner ends of said flange portions having angularly extending keying flanges overlying and imbedded in inner surfaces of said supports in retaining the butts against displacement from the respective supports.

65 3. The combination with adjacent wall portions of two supports adapted to be hingedly coupled with spaced slits on said walls arranged angularly to and opening through adjacent abutting

70 75

edges of said walls and through inner and outer surfaces thereof, of a hinge comprising two butts having elongated attaching plates, means at adjacent edges of the plates for hingedly coupling the same, said plates being adapted to be mounted on outer surfaces of said supports, the ends of each plate having angularly extending flange portions arranged in said slits and of a length equal to the thickness of the wall portions of the supports, the inner ends of said flange portions having angularly extending keying flanges overlying and imbedded in inner surfaces of said supports in retaining the butts against displacement from the respective supports, outer surfaces of the supports having recesses intermediate the slits in said supports, and said attaching plates having socket portions fitting in the recesses of said supports.

4. The combination with supports adapted to be hingedly coupled and having slots arranged angularly to and opening through adjacent abutting surfaces and inner and outer surfaces of the supports, of a hinge comprising two butts, each butt having a flat attaching plate portion adapted for arrangement on the outer surface of a support, means hingedly coupling adjacent edges of the attaching plate portions of the butts in alignment with abutting surfaces of the supports, the ends of said butts having preformed L-shaped mounting members, one leg of said mounting members being adapted to enter the slots on the adjacent surfaces of the supports and of a length equal to the distance between inner and outer surfaces of the supports, and the other legs of said members being arranged upon inner surfaces of the supports adjacent the slots therein and imbedded in said surfaces in keying the butts against displacement from each support.

5. The combination with supports adapted to be hingedly coupled and having slots arranged angularly to and opening through adjacent abutting surfaces and inner and outer surfaces of the supports, of a hinge comprising two butts, each butt having a flat attaching plate portion adapted for arrangement on the outer surface of a support, means hingedly coupling adjacent edges of the attaching plate portions of the butts in alignment with abutting surfaces of the supports, the ends of said butts having preformed L-shaped mounting members, one leg of said mounting members being adapted to enter the slots on the adjacent surfaces of the supports and of a length equal to the distance between inner and outer surfaces of the supports, the other legs of said members being arranged upon inner surfaces of the supports adjacent the slots therein and im-

bedded in said surfaces in keying the butts against displacement from each support, and said last named legs including prongs.

6. A hinge for hingedly coupling two supports at adjacent abutting wall portions of the supports, said wall portions having slots opening through adjacent and inner and outer surfaces thereof, said hinge comprising substantially similar butts having attaching plates adapted for arrangement on inner and outer surfaces of the supports, means at adjacent edges of the attaching plates for hingedly coupling said butts in alignment with abutting surfaces of the supports, each attaching plate having preformed L-shaped mounting flanges, one part of each flange extending angularly to the attaching plate and adapted to be arranged in the slots in the wall of the respective support in connection with which the butt is mounted, said part being equal to the distance between inner and outer surfaces of the supports, the other part of each flange extending angularly to the end of the first named part and being disposed upon the inner surface of said wall, and means for keying the last named part to said wall of the support when the butt is mounted on the support in retaining the butt against displacement therefrom.

7. A hinge for hingedly coupling two supports at adjacent abutting wall portions of the supports, said wall portions having slots opening through adjacent and inner and outer surfaces thereof, said hinge comprising substantially similar butts having attaching plates adapted for arrangement on inner and outer surfaces of the supports, means at adjacent edges of the attaching plates for hingedly coupling said butts in alignment with abutting surfaces of the supports, each attaching plate having preformed L-shaped mounting flanges, one part of each flange extending angularly to the attaching plate and adapted to be arranged in the slots in the wall of the respective support in connection with which the butt is mounted, said part being equal to the distance between inner and outer surfaces of the supports, the other part of each flange extending angularly to the end of the first named part and being disposed upon the inner surface of said wall, means for keying the last named part in said wall of the support when the butt is mounted on the support in retaining the butt against displacement therefrom, and said last named means comprising the imbedding of said second flange parts in the inner surface of the respective supports.

HERBERT TRAUMÜLLER.
